UNITED STATES PATENT OFFICE.

JOHN Q. TAYLOR, OF MEDIA, PENNSYLVANIA.

SAFETY-MATCH-BOX HOLDER.

Application filed November 2, 1926. Serial No. 145,815.

My invention relates to a holder or casing for safety match boxes, its object being to provide a very simple and inexpensive device that may easily be attached to the usual 5 match box, thereby providing a very attractive and serviceable pocket accessory, whereby the box may be readily opened, as for the removal of a match, and which will be instantly and automatically closed with its release. The scope of my invention extends 10 to whatever construction may be defined by or included within the terms or language of the appended claims.

In the drawing:

Figure 1 is a view in perspective of my 15 invention as applied to a match box;

Figure 2 is a central longitudinal section thereof;

Figure 3 is a transverse sectional view on 20 the line 3—3 of Figure 1;

Figure 4 is a view in perspective of the 25 casing portion of my invention, and

Figure 5 is a similar view of another form 30 of my invention.

My invention, in the form or embodiment shown in the drawing and briefly described, comprises a metallic casing, 10, of substantially the same shape as the usual 35 slidable type of safety match box, indicated generally as at 11, which, of course, is provided with the outer box portion, 12, and the slidable container portion, 13. The metallic casing, 10, is preferably formed of relatively thin sheet metal and is fitted over 40 the exterior of the match box, 11, as is clearly shown in Figures 2 and 3.

A space, 14, is formed between the oppositely disposed edges in the bottom of the casing, 10, for the purpose of receiving 45 the slides or arms, 15 and 16. Each of the slides or arms, 15 and 16, are provided with slightly upturned portions, 17, for the purpose of engaging the movable portion, 13, of the safety match box.

As shown in Figures 2 and 3, I utilize a 50 yieldable strip, 18, which may be secured in any desired manner to the slides or arms, 15 and 16, so as to have a tendency to keep the match box in a normally closed position.

To prevent the box portion, 13, from being 55 accidentally displaced from the slides or arms, 15 and 16, a sharp upturned edge may be provided on the uppermost end of the upturned portions, 17. When the box portion, 13, is pushed open, one of the slides will, of course, be pulled in the direction of

movement of this box portion, whereas the opposite slide will remain stationary by reason of the fact that its upturned portion, 17, will bear against the lower edge of the 60 stationary box portion, 12. This is clearly shown in Figure 1.

Elongated openings or cut-out portions, 19, are provided in the sides of the casing, 10, for the purpose of exposing the roughened or treated edges of the safety match 65 box.

In order to present a very striking appearance to my improved safety match box holder, I cover the thin metallic casing, 10, with a flexible covering, 20, such as leather or its substitutes. The covering, 20, is likewise provided with a pair of slots or cut-out portions, 21, which are adapted to align or register with the slots, 19, in the casing, 10. A snap fastener, 22, may be employed to secure the flaps or free ends of the covering, 20, and to facilitate the ready removal or replacement of the covering, 20, when desired. For the purpose of preventing the covering, 20, from sliding with respect to the casing, 10, I provide the casing with a plurality of cut-out points, 23, and preferably locate them near the corners of the casing, as is clearly illustrated in Figure 4 of the accompanying drawing.

In the form of my invention illustrated in Figure 5, a somewhat simplified structure is shown. In this instance, the relatively thin sheet metal cover, 10', will extend 90 around but three sides of the match box instead of completely around it, as previously described. The sheet metal cover, 10', is provided on its lower side with an off-set groove or depression, 24, for receiving the 95 slides or arms, 25 and 26. In this instance, the slides or arms, 25 and 26, are held together by means of a relatively thin coil spring, 27. It is understood, of course, that the elastic rubber, 18, previously described, 100 may be substituted for the spring, 27.

What I claim is:

1. A holder for safety-match boxes, comprising an open-ended casing in which the match box fits more or less snugly, members 105 slidably mounted in one wall of the casing and terminally formed to overlie the edge of the match-box cover and project into the path of movement of the match container when such match box is in the casing, and spring means to exert return pressure on either member when operated.

2. A holder for safety-match boxes, comprising an open-ended casing to more or less snugly receive the match box and permit movement of the match container through either open end, and two-part spring operated means freely slideable in the casing and adapted to be operated in the opening movement of the match container in either direction, the movement of one part of said spring means being resisted by the match-box cover and the other part being moved during opening movement of the container, the relative movements of the said parts inducing the spring tension necessary to return the container to normal position.

3. A holder for safety-match boxes, comprising an open ended-casing formed with

a channel in one wall, two members arranged in alignment in such channel and normally extending to the edges of the open ends of the casing, a spring means connecting the proximate ends of the members to exert a pull on either member when moved while the other is held, the free ends of the members having upturned ends to overlie the cover of a contained match box and extend into the path of movement of the match container thereof, whereby in the movement of the container in either direction one of the members is moved while the other member is held from following movement by the match box cover.

JOHN Q. TAYLOR.
